SCREW HOLDING ATTACHMENT FOR SCREW DRIVERS

Filed May 16, 1923

JOHN H. MOCKETT, JR.
INVENTOR.

Watson E. Coleman

ATTORNEY.

UNITED STATES PATENT OFFICE.

JOHN H. MOCKETT, JR., OF DENVER, COLORADO.

SCREW-HOLDING ATTACHMENT FOR SCREW DRIVERS.

Application filed May 16, 1923. Serial No. 639,338.

To all whom it may concern:

Be it known that I, JOHN H. MOCKETT, Jr., a citizen of the United States, residing at Denver, in the county of Denver and State 5 of Colorado, have invented certain new and useful Improvements in Screw-Holding Attachments for Screw Drivers, of which the following is a specification, reference being had to the accompanying drawings.

10 This invention relates to screw drivers, and particularly to attachments for holding screws thereto while the screws are being driven.

The general object of this invention is to 15 provide a very simple and effective device of this character which may be cheaply made and which will firmly hold the screw in engagement with the blade of the screw driver not only when the screw is first inserted but while it is being screwed home.

A further object is to provide a device of 20 this character in which the attachment is capable of being withdrawn from its screw-engaging position to permit the screw driver 25 to be used as ordinarily.

A still further object is to provide a screw holder particularly adapted for setting and extracting small machine screws in inaccessible places, and which is further adapted 30 to hold a washer against the head of the screw while the screw is being driven, thus insuring against loss of the washer when work is being done in dark places.

Another object is to provide a device of 35 this character which will permit the blade of the screw driver to be dressed at any time without removing the attachment but which may be readily shifted so as to permit the removal of the blade in case it is required.

40 Still another object is to provide a device of this character which will hold a very small or very short screw.

Other objects will appear in the course of the following description.

45 My invention is illustrated in the accompanying drawings, wherein:—

Figure 1 is a side elevation of a screw driver provided with my attachment and showing the screw holder in place upon the 50 blade of the screw driver;

Figure 2 is an elevation of the upper portion of the blade shown in Figure 1 but showing the screw holding sleeve retracted;

Fig. 3 is a top plan view of the construction shown in Figure 2;

Figure 4 is a section on the line 4—4 of Figure 2;

Figure 5 is a cross section of a modified form of blade;

Figure 6 is a face view of the blank used 60 in forming the sleeve 5.

Referring to these drawings, it will be seen that the screw driver consists of a shank and a handle. The shank has a relatively thin blade 1 which is illustrated as formed 85 integral with the shank portion 2 which is square in cross section and the portion 3 which is circular in cross section. This shank is mounted in an ordinary handle 10 having a ferrule 9. Any suitable handle 70 may be used, however.

Surrounding the square portion of the shank and slidably thereon is a sleeve 5 which is rectangular in cross section at its lower end so as to fit the square portion of 75 the shank and this sleeve at its lower end is operatively connected to a contractile spring 4, the lower end of this spring being in turn operatively engaged with the end of the handle of the screw driver by the ferrule 9. The 80 extremity of the sleeve 5 is formed with a struck-up lip 11 which is shown as engaging the upper coil of the spring. The upper end of the sleeve is longitudinally split, as at 5^a, and reduced in width or cut away, as at 5^b, 85 and the upper ends of these reduced portions are turned down at right angles to form opposed jaws 8 which are disposed in spaced relation to each other and at right angles to the longitudinal axis of the sleeve. These 90 jaws are disposed on each side of the blade portion 1 and normally the blade portion 1 projects through or beyond the jaws, as illustrated in Figure 2. These jaws in this case will rest upon the shoulder 1^a formed 95 at the junction of the portion 2 with the portion 1, the sleeve being urged in this direction by the contractile spring 4. It will be seen that the shanks of the jaws 8 because of the slit 5^a may be drawn apart and thus permit the insertion of screws having different diameters. The sleeve 5 is formed of one piece of metal having the form shown in Figure 6, the jaws being bent upon the dotted line.

100 Where the screw driver is to be used as ordinarily, the sleeve 5 will be retracted by the spring 4 upon the shank or blade until it strikes the shoulder 1^a and will be held in this position. When it is desired to use 110

the device for the purpose of holding a screw in place upon the blade the sleeve is drawn out and then the screw inserted laterally so that the extremity of the blade 1 will engage with the nick in the screw while the slot 10 will embrace the head of the screw, as shown in Figure 1. Under these circumstances the contractile spring 4 will act to draw the sleeve 5 toward the handle 10 and toward the headed end of the screw against the blade 1, thus holding the screw in place. If a washer is desired to be placed upon the screw, then the washer is first placed upon the screw and then the jaws 8 are engaged with the screw on the other side of the washer from the head, thus holding the washer against the head and the head against the blade 1. When the parts are thus engaged it is obvious that the screw 20 will be firmly held in place and that the screw driver may be inserted in otherwise inaccessible places and rotated to turn the screw in.

The device may be also used for the purpose of removing a screw already inserted and taking it out of an inaccessible or dark place where it is hard to see the screw. Under these circumstances the screw driver is first engaged in the ordinary manner with 30 the screw and the screw reversed, turning the screw out. After the head of the screw has been turned a slight distance the sleeve 5 is forced forward and then forced laterally against the shank of the screw just below the head and the jaws 8 will spring out to permit the head to pass into the slot 10. Then the screw driver may be turned to fully withdraw the screw and the screw will lift out with the screw driver.

40 It will be seen that the sleeves and jaws are made of a single stamping of sheet metal. If of tool steel it can be heated and pressed to shape in a suitable form and then tempered. The jaws should possess some degree 45 of elasticity, not for the purpose of holding the screw but to permit the insertion of a screw having a shank of greater diameter than the distance between the jaws and then, the screws being released, the jaws will assume their original shape. The sleeve when properly fitted to the blade or shank will freely slide back and forth thereon but cannot turn and get into a wrong position. This screw driver is particularly useful in connection with the setting and extraction of 55 small machine screws in inaccessible places which cannot be reached by the fingers of the operator and where the screw would be likely to drop. Split or lock washers 60 used with machine screws to prevent the latter from working loose after they have been set in place can be applied in connection with the screw, as heretofore stated. This device will hold the washers in position on the 65 screw until the latter is securely set or start-

ed, thus insuring against loss of the washer when work is being done in uncertain light or semi-darkness.

The point of a screw driver sometimes requires dressing and this can be done without removing the attachment from the blade. However, should it be desired to remove it this is easily accomplished by merely unhooking the spring at the end resting against the ferrule. Then if the point of the tool is 75 broken or the blade becomes bent, the attachment may be quickly and easily removed, the blade repaired, shortened if necessary, and again attached, when it will operate as before. With my device the screw is not automatically released from the jaws as it is being driven, as this is neither necessary nor desirable, as if the screw is so released from the jaws when being driven it leads to defacement of the object into which the screw 80 is being driven as the jaws are forced apart or the ejection of the screw before it is started by the force of the coiled spring.

While I have illustrated in Figures 1 and 2 the shank as being square in cross section, 90 I do not wish to be limited to this, as a relatively narrow and thin shank might be used. In this case, however, the shank is rectangular in cross section, as illustrated in Figure 5, instead of being square, as illustrated in 95 Figure 4. Any form of shank, however, which will provide the shoulder 1^a and which will prevent the sleeve 5 from turning upon the shank will be suitable for this purpose. Attention is called to the fact that this 100 screw holder is also adapted to hold the washer in place around machine screws, thus insuring against loss of the washer and permitting the washer to be used in place on the screw before the screw is inserted or 105 driven.

I claim:—

1. A screw driver having a shank formed with a blade at its extremity, the shank having a many-sided portion, a sleeve sliding 110 upon the many-sided portion and fitting the same, the sleeve at its extremity being reduced and longitudinally split to form two longitudinally extending tangs, the material of the sleeve at the end of said tangs being 115 angularly bent at right angles to the axis of the sleeve to form opposed resilient jaws spaced from each other to admit the blade between them and to receive a screw head, and a spring attached at one end to the 120 handle of the screw driver and at the other end attached to said sleeve and acting to retract the sleeve and draw a screw head against the blade.

2. A screw driver having a handle and a 125 shank formed to provide a blade, the shank beyond the blade being many-sided, a many-sided sleeve of thin metal fitting the shank and sliding thereon, the sleeve at its extremity remote from the handle being longi- 130

tudinally split at one corner of the rectangular sleeve to thereby provide opposed shank portions angularly bent at their extremities to provide jaws spaced from each other a distance equal to the thickness of the blade, said jaws being laterally expansible and contractible, and a coiled contractile spring surrounding the shank and engaged at one end with the sleeve and at its other end with the handle and acting to retract the shank.

3. A screw driver having a handle and a shank, the shank being rounded for a distance from the handle, then being rectangular in cross section and then being formed to provide a relatively thin blade, a sleeve sliding on the rectangular portion of the shank and fitting the same, the sleeve at its end

adjacent to the point of the blade being cut away on each side and longitudinally split between the cut away portions to form two resilient tangs, the extremities of the tangs being angularly bent to form opposed jaws spaced from each other a distance equal to the thickness of the blade whereby the jaws may be retracted upon the blade, and a coiled contractile spring surrounding the shank and attached at one end to the handle and at the other end to the sleeve and acting to retract the sleeve, the sleeve when retracted bearing against a shoulder on the shank.

In testimony whereof I hereunto affix my signature.

JOHN H. MOCKETT, JR.
